[57]

CLAIM

The ornamental design for a combined ring and article holder, as shown and described.

DESCRIPTION

FIG. 1 is a right side elevational view of a combined ring and article holder showing my new design;
FIG. 2 is a front elevational view;
FIG. 3 is a rear elevational view;
FIG. 4 is a top plan view; and
FIG. 5 is a left side elevational view, the broken line showing of a writing implement being illustrative of environment only.
